[57] CLAIM

The ornamental design for an armoire, as shown and described.

DESCRIPTION

FIG. 1 is a perspective view of an armoire in accordance with the preferred embodiment of this invention;

FIG. 2 is a side elevational view of the armoire of FIG. 1, the other side being a mirror image; and,

FIG. 3 is a front elevational view of the armoire of FIG. 1. The top, bottom and back of the armoire are unadorned and form no part of the invention.
